ELECTRIC SWITCH

Filed Feb. 18, 1927

Inventor:
James H. Clark

UNITED STATES PATENT OFFICE.

GEORGE L. CRAGG, OF CHICAGO, ILLINOIS, ASSIGNOR TO HARRY A. DOUGLAS, OF BRONSON, MICHIGAN.

ELECTRIC SWITCH.

Application filed February 18, 1927. Serial No. 169,280.

My invention relates to electric current conducting winding elements and to circuit controlling switches in electrical association therewith.

5 The invention finds particular utility in connection with spark producing circuit systems employed for producing sparks in cylinders of internal combustion engines that are employed in the power plants of automobiles or other automotive vehicles. The invention has for its general object the provision of an improved assembly of the winding elements, the cores of such elements, and the associated switches whereby the switches 10 and the circuit terminals thereat are guarded from unwarranted access and the combined structures are simplified and occupy less space than hitherto.

In carrying out my invention, a casing 20 is provided for the switch, this casing having a rear wall in close proximity both to the core and to the winding element of the device so that such core and winding element may guard the switch, at the rear 25 thereof, from unwarranted access. While the switch casing is thus closely approximated with both the winding and its core, the invention is not to be limited to this arrangement inasmuch as the winding and 30 core are individually in protecting relation to the casing. In the preferred embodiment of the invention, the casing has a rearwardly extending wall or skirt portion surrounding one end of the core, this core end desirably 35 projecting beyond the winding. This wall or skirt portion of the casing effectively cooperates with the winding element and with the core of the winding element in guarding the switch structure.

40 I will explain my invention more fully by reference to the accompanying drawing in which Fig. 1 illustrates a winding element in longitudinal section and the switching mechanism in association therewith partially in 45 section and partially in elevation; Fig. 2 is a sectional view on line 2—2 of Fig. 1, on a larger scale; Fig. 3 is a sectional view on line 3—3 of Fig. 1, on a larger scale; Fig. 4 is a sectional view on line 4—4 of Fig. 1, on a 50 larger scale; Fig. 5 is a sectional view on line 5—5 of Fig. 3, on a smaller scale; Fig. 6 is a rear view of the locking mechanism; and Fig. 7 is a diagram illustrating the use of my invention in connection with the igni-

tion system of an internal combustion engine.

The hollow current conducting element illustrated is inclusive of a winding 1 constituting the primary of an induction coil that is employed in a circuit serving to produce sparks in the cylinders of an internal combustion engine. Another winding 2 is illustrated which, in this instance, is secondary to the winding 1, this secondary winding being shown as being surrounded by the primary winding. The primary winding has one terminal grounded through a circuit interrupter 3 whose contacts are shunted by a condenser 4. The other terminal of the primary winding is grounded through a battery 5. The secondary winding 2 also has one terminal grounded through the circuit interrupter 3, the other terminal of the winding 2 being connected with the revolving arm 6 of a distributor whose waiting contacts 7 are successively engaged by said arm, these waiting contacts being connected with the electrodes 8 of spark plugs or other gas igniting elements that are contained in the various cylinders of the internal combustion engine, indicated at 9, that is equipped with the ignition system.

The windings 1 and 2 are tubular, the bore of the inner winding having a flattened tubular lining 10 of insulation. A magnetizable core 11 is shown disposed within said lining, this core extending rearwardly beyond the windings 1 and 2. A cup-shaped cap 12 receives the rear end of the core 11, the skirt of the cap surrounding said core. A binding post 13 passes through and is assembled with the end wall of the cap 12 and receives the external circuit wire 14 that leads to the rotating distributor contact 6, this binding post being in electrical connection with one terminal of the secondary 2. The cap 12 is held in relation to the core 11 in any suitable way. A body of viscous insulating material 15 may fill or partially fill the space between the rear ends 100 of the windings 1 and 2 and the cup-shaped section 16 of the metallic sheathing which encases the entire structure. The end wall of the cup-shaped section 16 of said sheathing is formed with a central perforation 105 whose marginal portion enters an annular groove formed in the cap, as indicated at 17. Binding posts 18 and 19 are carried by and

insulated from the end wall of the cap section 16 of the sheathing, these binding posts receiving external wires 20 and 21, the binding post 18 being connected with one terminal of the primary 1 through the switching mechanism of my arrangement and directly with the remaining terminal of the secondary winding, as shown most clearly in Fig. 7. The binding post 19 is connected directly with the other terminal of said primary. The sheathing about the structure includes a cylindrical portion 22 which enters the skirt of the cup-shaped section 16 of the sheathing, the portion 22 being suitably assembled with the skirt of this cup-shaped section 16, as by spot welding. Liners 22' may be interposed between the sheathing section 22 and the winding 1.

The front end of the cylindrical portion 22 of the sheathing receives a lock casing which is inclusive of a cup-shaped portion 23 whose end wall is innermost and whose rim is outwardly beaded, as indicated at 24, and which receives the flange 25 that surrounds the front end of the sheathing section 22. The cup-shaped portion 23 of the lock casing is closed by a cap 26 whose skirt is contracted behind the bead 24 whereby the cap 26 is held in place. Mounting screws 27 pass through the mounting plate 28 and through the end wall of the cap 26 whereby the entire structure may be mounted. The end wall of the cap 26 is lined by a disc 29 which is held in place by the sleeve rivet extensions 30 formed upon the end wall of the cap 26 and in which the screws 27 are received. A locking guard, preferably in the form of a shell 31, has a flange 32 at its outer end which is rigidly clamped between the disc 29 and the end wall of the cap 26. The shell 31 projects inwardly into the lock casing and preferably through the rear wall of this casing. A tumbler barrel 33 is mounted to turn in the shell 31, this tumbler barrel carrying tumblers 34 which are receivable at their ends in slots 35 that are formed in opposite sides of said shell 31. These tumblers are operable by a key 36, that is acceptable by the tumbler barrel, to be withdrawn from said slots when the key is inserted. When the tumblers are withdrawn, the tumbler barrel may be turned to a position in which the primary circuit may be either opened or closed, as will more fully appear. When the primary circuit is opened, the key may be withdrawn to permit the tumblers to enter said slots, the tumblers then serving to lock the primary circuit in open adjustment, as will more fully appear.

The switching mechanism illustrated is disposed within a cap 37 of insulation, this cap having a rearwardly extending skirt portion 38 which surrounds the front end 65 of the core 11 and a forwardly extending

skirt portion 39 which surrounds the switching mechanism, there thus being a common wall 40 of the cap 37 which is between the two skirts 38 and 39 and from which these skirts project in opposite directions, the rear face of this wall 40 being in engagement with the front end of the core 11. The space surrounding the cap 37 is suitably occupied with a filling material of insulation, as indicated at 41, in accordance with common practice and, if desired, the cap 37 and cap 12 may have rings of insulation 42, 43 respectively interposed between the same and the secondary winding 2. The cap 37 desirably has its rear skirt of oblong shape 80 to correspond to and snugly receive the front end of the flattened lining 10, Fig. 5, so that the cap 37 is positively held from rotation with respect to said lining and with respect to the core 11 which is tightly received within the lining. The cap skirt 38 has its rear termination in front of and preferably in contact with the ring of insulation 42 of the winding element and snugly engages the front end of the core surrounded thereby. The entire cap is substantially coaxial with the winding element and is approximately of the same diameter, being arranged in tandem with the winding element. The switching mechanism illustrated is inclusive of two metallic contacts 44 and 45 which are hollow and receive metallic springs 46 whereby these contacts are pressed inwardly toward each other. These springs are contained within spring barrels 47 that are in spaced apart relation, these spring barrels being rigidly secured to the contact carrier 48 which is inserted within the cap 37 and is surrounded by the front skirt 39 of this cap. The carrier 48 is of insulation and is formed with a lateral groove 49 which receives a rib 50 that projects inwardly from the cap skirt 39 whereby said contact carrier is held from rotation. Said contact carrier is in the form of a ring having a cylindrical bore which receives another contact carrier 51, the latter contact carrier being cylindrical and rotatable within the contact carrier 48. A contacting bar 52 is carried by the contact carrier 51 and extends diametrically therethrough. The contacts 44, 45 and 52 are arranged in the same zone and in a plane perpendicular or transverse to the common axis of the windings 1 and 2, the contacts 44 and 45 being thus radially disposed. When the contact carrier 51 is turned in one position, its contacting bar 52 is out of engagement with said contacts which are then received within recesses 53 formed in opposite sides of the carrier 51. The ignition circuit is then opened. When the latter contact carrier is reversely positioned, its contacting bar 52 engages both contacts whereby the ignition circuit is closed. The key 36 is adapted to 130

place the contact carrier 51 in either an ignition circuit opening position or an ignition circuit closing position. To this end, the tumbler barrel 34 has an oblong inner 5 extension 54 which is receivable within an oblong slot 55 which is formed in the enlarged front end of the carrier 51, the front enlargement of this carrier being received in the step formation in the carrier 48 so that 10 the rearward movement of the carrier 51 is prevented, the forward movement of this carrier 51 being prevented by being in engagement with the lock shell 31. Assuming that the ignition circuit is open and is to be 15 closed, the key is inserted to withdraw the tumblers 34 from the slots 35 whereafter the tumbler barrel is turned to bring the contacting bar 52 into engagement with the contacts 44 and 45. When the ignition circuit 20 is again to be opened, the tumbler barrel is turned by the key to bring the tumblers into register with the slots 35 whereafter the key is withdrawn to permit the tumblers to enter said slots, the contacting 25 bar 52 being now out of engagement with the contacts 44, 45.

It will be apparent that the structure of my invention is very compact, a minimum of space being required by the connections of 30 the wires with the contacts 44 and 45, as illustrated most clearly in Fig. 1, where said wires are shown as passing through the rear wall 40 into connection with said contacts on one side of said wall and toward the rear 35 end of the structure through the space between the core 11 and the lining 10.

The cap 37, which constitutes a casing element for the switching mechanism, is thoroughly protected at its rear by the core 40 11 substantially abutting the same to prevent tampering with the switch and its wiring or connections that pass through the rear wall of this casing. The switch is well guarded at its front by the lock casing 45 which comprises the cup 23 and its lock supporting closure 26, 29 and by the guard or shell 31 and the tumbler barrel 33 constituting a closure for the opening in the end wall of cup 23 through which the tumbler barrel 50 has actuating connection with the contact carrier 51. The front ends of the windings are also closely approached to the switch casing 37 to also guard the switch, the core 11 preferably extending forwardly 55 beyond the front ends of the windings into the rear skirt of said casing to further the switch guarding function of the core. The skirt 38, projecting rearwardly from the switch casing, of itself serves to guard the 60 switching mechanism and has this purpose furthered when it is closely approached to the windings and receives the front end of the core. There is an advantage in assembly where the core enters the rearwardly 65 extending wall portion 38 of the casing apart

from the lock, the invention not being limited to the presence of wall 40.

Changes may be made without departing from the invention.

Having thus described my invention, I claim:

1. The combination with an electric current conducting winding element having a magnetizable core portion; of a circuit controlling switch in electrical association with 75 said winding element; a casing for the switch having a rearwardly extending wall closely surrounding one end of the core; and a locking structure in controlling relation to the switch.

2. The combination with an electric current conducting winding element having a magnetizable core portion; of a circuit controlling switch in electrical association with 85 said winding element; a casing for the switch having a rearwardly extending wall extending into close proximity to the core; and a locking structure in controlling relation to the switch.

3. The combination with an electric current conducting winding element; of a circuit controlling switch in electrical association with said winding element; a casing for the switch having a rear wall through 95 which electrical connection with the switch is effected and having a rearwardly extending skirt terminating in close proximity to said winding element; and a locking structure in controlling relation to the switch.

4. The combination with an electric current conducting winding element; of a circuit controlling switch in electrical association with said winding element; a casing for the switch having a rearwardly extending skirt terminating in close proximity to said 105 winding element; and a locking structure in controlling relation to the switch.

5. The combination with an electric current conducting winding element having a magnetizable core portion projecting beyond 110 the front end thereof; of a circuit controlling switch in electrical association with said winding element; a casing for the switch having a rear wall through which electrical connection with the switch is effected and 115 a rearwardly extending skirt surrounding the projecting end of the core; and a locking structure in controlling relation to the switch.

6. The combination with an electric current conducting winding element having a magnetizable core portion; of a circuit controlling switch in electrical association with 120 said winding element; a casing for the switch having a rear wall through which electrical connection with the switch is effected and a rearwardly extending skirt 125 closely surrounding one end of the core; and a locking structure in controlling relation to the switch.

7. The combination with an electric current conducting winding element having a magnetizable core portion; of a circuit controlling switch in electrical association with said winding element; a casing for the switch having a rear wall through which electrical connection with the switch is effected and a rearwardly extending skirt extending into close proximity to the core; and a locking structure in controlling relation to the switch. 55
8. The combination with an electric current conducting winding element having a magnetizable core portion; of a circuit controlling switch in electrical association with said winding element; a casing for the switch having a rearwardly extending wall closely surrounding one end of the core and having its rear termination in front of the winding element; and a locking structure in controlling relation to the switch. 60
9. The combination with an electric current conducting winding element having a magnetizable core portion; of a circuit controlling switch in electrical association with said winding element; a casing for the switch having a rearwardly extending wall extending into close proximity to the core and having its rear termination in front of the winding element; and a locking structure in controlling relation to the switch. 65
10. The combination with an electric current conducting winding element having a magnetizable core portion-projecting beyond the front end thereof; of a circuit controlling switch in electrical association with said winding element; a casing for the switch having a rear wall through which electrical connection with the switch is effected and a rearwardly extending skirt surrounding the projecting end of the core and having its rear termination in front of the winding element; and a locking structure in controlling relation to the switch. 70
11. The combination with an electric current conducting winding element having a magnetizable core portion; of a circuit controlling switch in electrical association with said winding element; a casing for the switch having a rear wall through which electrical connection with the switch is ef- 75
- fect and a rearwardly extending skirt closely surrounding one end of the core and having its rear termination in front of the winding element; and a locking structure in controlling relation to the switch. 80
12. The combination with an electric current conducting winding element having a magnetizable core portion; of a circuit controlling switch in electrical association with said winding element; a casing for the switch having a rear wall through which electrical connection with the switch is ef- 85
- ected and a rearwardly extending skirt ex- tending into close proximity to the core and having its rear termination in front of the winding element; and a locking structure in controlling relation to the switch. 90
13. The combination with an electric current conducting winding element; of a circuit controlling switch in electrical association with said winding element; a casing for the switch having a rear wall through which electrical connection with the switch is ef- 95
- ected and having a rearwardly extending skirt terminating, at its rear end, in front of and in close proximity to said winding element; and a locking structure in controlling relation to the switch. 100
14. The combination with an electric current conducting winding element; of a circuit controlling switch in electrical association with said winding element; a casing for the switch having a rearwardly extending skirt terminating, at its rear end, in front of and in close proximity to said winding element; and a locking structure in controlling relation to the switch. 105
15. The combination with an electric current conducting winding element having a magnetizable core portion; of a circuit controlling switch in electrical association with said winding element; a casing for the switch having a rearwardly extending wall surrounding one end of the core and having its rear termination in front of the winding element; and a locking structure in controlling relation to the switch. 110

In witness whereof, I hereunto subscribe my name.

GEORGE L. CRAGG.
